SET OF EDUCATIONAL PLAYING CARDS

Arvil Eugene Davis, 1509 11th St.,
Wichita, Tex. 76301

Filed Aug. 21, 1967, Ser. No. 8,327

Term of patent 14 years

(Cl. D34—13)

The figure is a plan view of a set of educational playing cards showing my new design.

The backs of the cards are conventional.

The essential features reside in the full line portions.

I claim:

The ornamental design for a set of educational playing cards, as shown and described.
